UNITED STATES PATENT OFFICE.

ISRAEL B. COHEN, OF NEW YORK, N. Y.

DESIGN FOR A HANDLE FOR FEATHER DUSTERS.

SPECIFICATION forming part of Design No. 26,199, dated October 20, 1896.

Application filed September 15, 1896. Serial No. 605,949. Term of patent 7 years.

To all whom it may concern:

Be it known that I, ISRAEL B. COHEN, of New York, in the county and State of New York, have invented a new and original Design for a Handle for a Feather Duster, of which the following is a full, clear, and exact description.

Reference is to be had to the accompanying drawings, forming a part of this specification, in which similar characters of reference indicate corresponding parts in all the figures.

Figure 1 is a perspective view of my handle. Fig. 2 is an enlarged plan view of the head of the same, and Fig. 3 is an end view. My design consists of a series of cones A of approximately the same size, having rounded bases B, and so placed as to present the appearance of being nested. These are formed upon the end of the handle which is intended to receive the feathers and with the bases of the cones outward. The bottom cone appears to be longer than the others, as more of it is visible. It merges into the handle portion C, which may be shaped as desired. The upper or outer cone is slightly smaller than the others and has sides of less angle. All of these cones are provided with holes D, extending from the base toward the apex of the cone.

I have shown four cones upon my duster-handle, but this number might be made less or more without essentially changing the design.

My design pertains to the shape of the head or base of the handle only.

The principal feature of my design is the cones at the base of the handle, which have the appearance of being nested and with the lines of the inner or lower one merging smoothly into the lines of the handle.

A second leading feature of the design is the cones, all being approximately of the same diameter and having the appearance of being nested.

A third leading feature of the design is the cones of approximately the same size with rounded bases and having the appearance of being nested.

I claim—

The design for duster-handles, substantially as shown and described.

ISRAEL B. COHEN.
